UNITED STATES PATENT OFFICE.

WINFIELD S. DRISKELL, OF GRETNNA, NEBRASKA.

GRAIN-DOOR.

No. 878,050.

Specification of Letters Patent.

Patented Feb. 4, 1908.

Application filed April 26, 1906. Serial No. 313,832.

To all whom it may concern:

Be it known that I, WINFIELD S. DRISKELL, a citizen of the United States, and a resident of Gretna, in the county of Sarpy and 5 State of Nebraska, have invented certain new and useful Improvements in Grain-Doors, of which the following is a specification.

My invention relates to grain doors for 10 cars, more particularly to doors of this class which are vertically slidable within fixed guides and swingable inwardly for hanging, when not in use, adjacent the roof of the car.

The objects of my invention are to provide, in doors of this class, devices facilitating the handling of the door in hanging the same adjacent the car roof, means permitting the introduction of a filling spout over the door when filling the car with grain, an outwardly opening relief door section having simple and effective retaining devices which may be easily released to permit opening of the relief section and the removal of the grain immediately adjacent the door, and 25 certain other constructions and arrangements as will be detailed hereinafter.

Constructions embodying my invention are shown in the accompanying drawings in which

30 Figure 1 is an exterior elevation of a portion of a car having the door thereon, Fig. 2 is an interior elevation of the same, Fig. 3 is a transverse sectional view thereof, Fig. 4 is a detail plan section of one of the slidable 35 retaining plates and bars for the relief section of the door, and Figs. 5 and 6 are detail perspective views of the upper and lower hook and pivot bars.

In the drawings 1 represents the side of a 40 car having therein the door opening 2, the roof of the car being indicated at 3 and the floor at 4. On the inside of the car adjacent the door opening are the vertically extending guide strips 5 between which is held the 45 grain door body comprising an upper and a lower portion, the upper portion consisting of the sections 6 and 7 connected by the hinges 8 on the inside of the door, and the lower portion consisting of the sections 9 and 50 10 connected by the hinges 11 on the outside of the door. The guide strips 5 extend slightly below the lower edge of the section 9

and above the upper edge of the section 6. The length of each of the three upper sections 6, 7 and 9 is greater than the width of 55 the door opening so that said sections when in position extend over the inside of the door framing. The length of the section 10 is made slightly less than the width of the door opening so that said section, which forms 60 the relief door before mentioned, may swing outwardly as indicated in dotted lines in Fig. 3 to permit removal of the grain near the door and relieve the pressure thereof on the door before opening it entirely to unload 65 the car.

When the car is filled with grain the said section 10 is held in position by the transversely slidable retaining plates 12 which are held on the outside of the section at the ends 70 thereof by means of the bolts 13 passing through the slots 14 in the plates, as shown. The retaining plates when extended pass inside the door framing, as shown in Fig. 4, and prevent the section from being forced 75 outwardly by the pressure of the grain thereon. As a means for actuating the plates I provide at the center of the section 10 a vertically extending crank shaft 15 which is journaled in suitable bearings 16 and 17 at 80 the top and bottom of the section, respectively. In said shaft near each of the bearings thereof are formed the rectangular loops 18, to each side of which are connected the straps 19 extending to and connected with 85 the retaining plates 12, as shown. At the center of the crank shaft is a handle 20 by which the shaft may be turned to draw the connecting straps and retaining plates in toward each other or to push the same outwardly for engagement with the door framing. 90

The ends of the connecting straps 19 after attachment to the retaining plates are bent outwardly to form the points 21 which are adapted to enter the recesses 22 in the door 95 framing, as shown in Fig. 4, to hold the section from displacement inwardly before the car is filled with grain. On the sections 7 and 9 are straps 23 having similar points formed on the ends thereof and adapted to 100 enter recesses in the door framing, the said straps being connected to the sections by bolts 24 passing through slots in the straps, and the straps being jointed near the center

of the sections so that by pushing the same downward the points may be disengaged from the door frame as indicated by the dotted lines in Fig. 1. The section 6 is preferably held against inward displacement by the hooks 25 which are engaged with the eye bolts 26 on the door framing. The lower bearing 17 of the crank shaft is formed from the central portion of a metal bar which is 10 extended along the lower edge of the section 10 to stiffen the same and prevent outward bulging thereof from pressure of the grain thereon.

At each end of the section 7 between the 15 same and the door framing are straps 27 which are connected by bolts to said section 7 and extend upwardly between the section 6 and the door framing as shown in Fig. 3 and by the dotted lines in Fig. 2. Above the 20 upper edge of the section 6 said straps are bent inwardly over the said edge of the section 6 and are thence formed into the round pivot bars 28 which extend laterally beyond the guide strips 5 and are then turned upwardly and again outwardly to form hooks 29 as shown in Fig. 5. Secured to the door framing are the vertically extending guide rods 31 with which each of the bars 28 are connected by means of two rings 32 passing 25 diagonally around the pivot bars and guide rods as shown in Figs. 2 and 3. The said rings form slideable and pivotal connection between the pivot bars and guide rods and, by the use at each connection of the two 30 rings passing diagonally around the connected members in opposite planes, the pivot bars at each side of the door are kept in horizontal alinement and prevented from binding or sticking when sliding the same on 35 the guide rods. Adjacent the roof of the car and directly above the hooks 29 are secured the double loops or stirrups 33 with the upper loop of which said hooks 29 engage when the door portion formed by the sections 6 and 7 40 is raised to the top of the guide rods and swung inwardly and up toward the roof of the car on the axis formed by the pivot bars 28. At a suitable position on one of the 45 roof beams is secured a loop 34 with which the hook 35, carried on the inside of the section 7 adjacent the lower edge thereof, may be engaged to support the inner side of the door portion when the same is raised to horizontal position adjacent the car roof, as 50 shown by the dotted lines in Fig. 3. The said hook 35 also forms a convenient handhold for raising the door portion before swinging the same to the horizontal position. Secured to the inside of the door section 9 55 near the upper corners thereof are straps 36 which at their upper ends are formed into the pivot bars 37 which extend laterally and are bent upwardly and outwardly as shown

in Fig. 6 to form hooks 38 similar to the hooks 29 on the pivot bars 28. The pivot bars 37 are connected with the guide rods by rings 32 in the same manner as the pivot bars 28. The operation in hanging up the lower door portion comprising the sections 9 and 10 is similar to that in hanging the upper 70 door portion, the hooks 38 engaging the lower loops of the stirrups 33, and the section 10 having thereon a hook 39 serving as a handhold for lifting the door and engageable, as shown by the dotted lines in Fig. 3, 75 with the loop 40 carried by the section 7.

In filling the car with grain, in order to permit a sufficient space above the door for the introduction of a filling spout from the elevator, the upper section 6 of the door is 80 swung inwardly as shown by the dotted lines in Fig. 3, when the car is almost filled the section being again raised to position and secured by means of the hooks 25 and eye bolts 26.

In emptying the car the handle 20 and the crank connections therefrom to the retaining plates 12 furnish a powerful leverage system by which the relief door section may be easily opened notwithstanding the great pressure 90 of the grain thereon. In hanging up the door when the car is not in use for hauling materials requiring the use of the doors, the door portions may be easily handled as each portion comprises only about one-half of the 95 entire door so that the weight of one portion is not enough to make it difficult to lift. It may be noted further that the doors are always attached to the car and carried in such position as to be entirely out of the way yet 100 readily accessible and easily placed in position when required for use.

Now, having described my invention, what I claim and desire to secure by Letters Patent is:—

1. In a vertically slideable and swingable grain door, the combination with vertical guide rods and laterally extending pivot bars carried by the door and slideably and pivotally connected with the guide rods, of stirrups 110 secured adjacent the car roof, and hooks formed on the ends of the pivot bars, said hooks being engageable with the stirrups by raising the door to the top of the guide rods and then swinging the same on the axes of 115 the pivot bars.

2. In a two-part vertically slideable and swingable grain door, the combination with vertical guide rods and laterally extending pivot bars carried by each part of the door, of rings passing diagonally around the pivot bars and guide rods to slideably and pivotally connect the same, double stirrups secured adjacent the car roof, hooks formed on the ends of the pivot bars, said hooks being engageable with the stirrups by raising the 125

door parts and then swinging the same on the
axes of the pivot bars, means carried adja-
cent the car roof for supporting one side of
the upper door part, and means carried on
5 said upper door part for supporting one side
of the lower door part.

In testimony whereof I have hereunto sub-

scribed my name in the presence of two
witnesses.

WINFIELD S. DRISKELL.
